PORTABLE POLAROGRAPHIC HALF CELL

Rolf Karl Ladisch, Lansdowne, Pa., assignor to the United States of America as represented by the Secretary of the Army

Application August 12, 1953, Serial No. 373,928

5 Claims. (Cl. 204—195)

(Granted under Title 35, U. S. Code (1952), sec. 266)

The invention described herein may be manufactured and used by or for the Government for governmental purposes without the payment to me of any royalty thereon.

The present invention relates to portable polarographic half cells such as are used in qualitative and quantitative analyses of certain solutions.

In using a polarograph for studying diffusion currents, a calomel half cell is commonly employed as a reference electrode in series with the dropping mercury electrode. Half cells in wide use, such as those described by J. J. Lingane and H. A. Laitinen in Ind. Eng. Chem., Anal. Ed., Vol. 11, p. 504 (1939) and G. S. Smith in The Analyst, Vol. 75, p. 215 (1950) cannot be moved about freely because shaking them sometimes causes inaccuracies of 1-3 millivolts or even more, and full accuracy may not be restored until five to six hours have elapsed. Besides, these prior art structures must be kept in an upright position to maintain the original cleanliness of the platinum contact.

This invention aims to provide a non-polarizable, rugged half cell of low ohmic resistance, especially made to confine the mercury in a rigid support, so that the electrical contact between the platinum wire and the mercury is not disturbed under the conditions of polarographic procedure. A specific object is to confine the mercury by material which is porous to the mercury when the latter is subjected to pressure. The preferred porous material is glass frit; when choosing a frit of proper size the area of the mercury can be made equal to or several times larger than that of the mercury pool in a conventional half cell.

In the accompanying drawings forming a part of this specification,

Fig. 1 is a full size elevation of the half cell, showing a conventional lead for the platinum wire;

Fig. 2 is an enlarged longitudinal section, omitting the lead;

Figs. 3, 4 and 5 are respectively cross sections on lines 3—3, 4—4 and 5—5 of Fig. 1;

Fig. 6 is a reproduction of two curves made from actual tests with the half cell and a conventional mercury pool electrode; and

Fig. 7 is a diagrammatic sectional view partly in elevation showing a set-up including the half cell for analyzing a solution by polarographic methods.

Referring particularly to the drawings, Fig. 1 shows the completed half cell 10 with a lead 11 coupled thereto. The preferred construction (Figs. 2-5) comprises a generally tubular glass body 12 having a tubular fritted glass container 13 enclosed therein. The upper end of container 13 is open and has a constricted neck 13a of clear glass fused to the inwardly curved end walls of body 12 to be integral therewith. The annular space or chamber 14 between container 13 and tubular body 12 is designed to hold mercury, shown at 15, the mercury being completely trapped by the provision of a transverse glass partition 16 closing body 12. (The manner in which the mercury is introduced into annular space 14 will be described later.) A platinum wire 17 makes electrical contact with mercury 15 by being fused at 18 into the center of partition 16; wire 17 also extends outwardly from the partition. In lieu of a platinum wire, an ordinary tungsten-copper lead may be used. Lead 11 is electrically connected to the outer end of wire 17 by means of a globule of soft solder 19. The cupped lower end 20 of body 12 contains a mass of cement 21 to secure lead 11 against displacement besides insulating the wires. Some of the cement 21 aids in securing a flanged rubber cap 22 on the cupped end 20. There are several cement compositions which may be used here with satis-

2

factory results. The lower clear glass end of tubular container 13 is closed and may abut the platinum wire 17 as shown, but this is not necessary. Wire 17 may be long enough to reach to the inner wall of body 12 as shown. Within tubular container 13 a mass of calomel paste 23 is placed so that all but the constricted neck of container 13 is occupied by said paste. The open upper end of container 13 is closed by a plug or wad of glass wool 24, or other fibrous inert material may be used to keep the paste within the container.

Referring to Fig. 7, the described half cell has its principal portion immersed in a sealed cylinder 25 containing KCl solution 26, with a surrounding water jacket 27 having circulating water to keep the temperature of the cell substantially constant. Also located in the sealed cylinder 25 above the half cell is an open vessel 28 closed at the lower end by a very thin resin membrane 29 whose under surface is in direct contact with the KCl solution 26. My pending application Ser. No. 220,325, filed April 10, 1951, discloses vessel 28 in more detail. The open vessel 28 contains the solution to be tested (not shown) and a dropping mercury electrode 30 drops mercury 35 in the test solution in vessel 28 in the well-known manner. A battery 31 with a rheostat 32, a galvanometer 33, and a lead 34 to the dropping mercury electrode, are also shown. The circuit is completed by lead 11 connected to the rheostat. As the technique of using the described polarographic apparatus is well understood, no description thereof will be undertaken.

In making the half cell, fritted glass parts with nominal maximum pore sizes of 40 microns and 5 microns were used at random. The glass body of the half cell was placed in a desiccator and was evacuated by means of a high vacuum pump for at least one hour; then with the glass body still under vacuum, triple distilled mercury was admitted through a funnel in the lid of the desiccator in such a fashion that the mercury filled the fritted glass container 13. With frits of 40 microns pore size, the mercury penetrated the fritted glass walls of container 13 to occupy annular chamber 14 (as shown in Fig. 2) as soon as the pressure in the desiccator was restored to atmospheric pressure. With fine frits of 5 microns pore size, a pressure of 75 p. s. i. gage from a nitrogen cylinder was applied to the mercury to accomplish the same result; this latter operation was performed in a stainless steel bomb, to which the glass body of the half cell, with the mercury, had been transferred from the desiccator. After the mercury had been forced to occupy its intended chamber 14 in the half cell, the excess mercury in container 13 was shaken off. A paste consisting of mercurous chloride, special for calomel cells, and potassium chloride solution, special for calomel cells (both of which are procurable on the market) was mixed and was introduced into the interior of container 13 to substantially fill it, as shown in Fig. 2. Finally, the open end of container 13 was closed by fibrous glass plug 24.

The potential of the described cell was checked in saturated KCl solution against a saturated calomel electrode. The average deviation of all cells tested was 0.3 millivolts; these small deviations decreased even further after the cells came to equilibrium overnight.

Polarographic analyses of 1.00 millimolar and 2.00 millimolar cadmium sulfate (reagent grade) in 0.1 normal KCl solution were conducted in a Lingane-Laitinen H-cell. The test compartment was separated from the reference electrode by an agar plug as usual. For comparison, a conventional mercury pool-calomel reference electrode in saturated KCl solution was placed in the bottom of the H-cell adjacent to the test compartment, the half cell of the invention being likewise immersed in the saturated KCl solution above the mercury pool electrode. The surface area of the mercury pool was 3.8 sq. cm. In view of the fact that the potential of the pool electrode may become inaccurate under certain conditions, this electrode was prepared with extreme care, and once it had been set up in the thermostated H-cell, it was neither removed nor mechanically disturbed. The pool electrode was renewed whenever significant changes in its potential (as measured against a calomel electrode) became apparent despite the precautions taken. Removal of the test solution and cleaning of its compart-

ment were done with a suction tube. The test solution was freed from oxygen by purified nitrogen prior to the analysis, and nitrogen was passed over the solution during the analysis as is usual. The drop time of the capillary used was checked during each run at the half wave potential; it maintained a value of 4.89 ± 0.01 sec. The $m^{2/3}t^{1/6}$ value was found to be 1.83 at an applied potential of -0.700 v. versus SCE, at which the magnitudes of the diffusion currents were determined. The capillary cell equipment was kept at $25^\circ \pm 0.1^\circ$ C. by means of a thermostat control. The iR drop across the polarographic circuit was measured. All data were corrected for the iR drop and the residual current.

To detect possible time-dependent changes in potential of the described cell, five curves were drawn consecutively with readings based on the same test solution. Approximately 45 minutes elapsed between the first and the last measurements. The heights of the diffusion currents at an applied voltage of -0.600 v. versus SCE (i.e., close to the half wave potential) agreed with each other to better than ± 0.5 per cent.

Fig. 6 shows the 1 millimolar and 2 millimolar cadmium sulfate curves obtained with the mercury pool electrode and the described half cell. The diffusion currents measured at an applied potential of -700 mv. with the described half cell were within the ranges of 6.55 ± 0.02 microamperes for the 1 millimolar solution and 13.05 ± 0.05 microamperes for the 2 millimolar solution. The half wave potentials were read from individual curves for each reference cell at $\frac{1}{2} i_a$ (where i_a is the average diffusion current in microamperes during the life of the drop of mercury). The readings agreed among each other within 597 ± 0.5 millivolts. The comparative resistances in ohms were as follows:

Test Solution	Conventional Hg Pool Electrode	Half Cell
1 millimolar.....	1,310	1,230
2 millimolar.....	1,160	1,170

The diffusion current constant was calculated on the basis of the original Ilkovic equation with $m^{2/3}t^{1/6}$ being 1.83. (The Ilkovic equation is explained in Collection of Czechoslovak Chem. Comm., Vol. 6, p. 498; 1934.) The electrolysis was not diffusion controlled, since no maximum suppressor was present. The value found in this manner for I_d was 3.58, which is in very good agreement with the data of Buckley and Taylor (Res. Natl. Bur. Stand., Vol. 34, p. 97; 1945) who obtained 3.54 for cadmium ions in the absence of a maximum suppressor. The half wave potential of 597 ± 0.5 mv. agrees well with Lingane's value of 599 ± 2 mv. (J. Am. Chem. Soc., Vol. 61, p. 2099; 1939). Attention is directed to the relatively low ohmic resistance of the cell circuit which includes the resistance of the agar plug; evidently the resistance of the new cell is of the same order of magnitude as that of the conventional mercury pool.

These data show that the new reference electrode, which was handled frequently during the course of the investigation, performed very satisfactorily in polarographic analysis. The cell is rugged, reliable and accurate and is very compact, besides being easily handled and packaged. With the conventional mercury pool electrode, great care had to be exercised to arrive at equally precise results, but in routine polarographic analysis, precise results cannot be expected from the conventional electrode.

Although the portable calomel half cell of this invention has been described with particular reference to its use in polarographic analyses, because of the great importance of having a reference electrode in such analyses which is very stable, it is to be understood that the portable calomel half cell of my invention may be used wherever calomel reference electrodes are needed.

This application is a companion to applications filed by me, Serial Nos. 372,411, filed August 4, 1953, and 419,941 filed March 30, 1954.

What I claim is:

1. A portable calomel half cell comprising a closed glass body; a tubular container composed principally of fritted glass, said container being completely enclosed in and attached to said body at its upper end and being open

at its upper end but otherwise closed, calomel paste substantially filling said container, whose upper open end is closed by a porous plug; the fritted glass container and the glass body being spaced apart to provide an annular chamber within the glass body, said annular chamber being completely closed; mercury completely filling said annular chamber; and an electrical conductor passed through a wall of said glass body and entering the space between the fritted glass container and the glass body to make electrical connection with the mercury in said space.

5 2. A portable calomel half cell comprising a hollow glass body which is completely closed and sealed; a glass container composed principally of fritted glass, said container being completely enclosed in said glass body and having an open upper end which is attached to the glass body at the corresponding end; a transverse partition closing the glass body near its lower end; the fritted glass container and the glass body having no other connection or contact so that there is a closed chamber between the fritted glass container and the glass body; an electrical conductor passed through said partition and entering said closed chamber; mercury completely filling said closed chamber; calomel paste substantially filling said fritted glass container; and a porous plug inserted in the open upper end of said fritted glass container.

15 3. A portable calomel cell comprising a hollow tubular body which is completely closed and sealed; a glass container composed principally of fritted glass, said container being open at one end only and attached to the tubular body at said open end, said fritted glass container lying wholly inside said tubular body with its walls spaced from the inner walls of said body so as to provide a mercury-holding chamber defined by the inner walls of said body and the outer walls of said fritted glass container; 20 mercury completely filling said chamber; calomel paste substantially filling said fritted glass container; a porous plug inserted in the open upper end of said fritted glass container; and an electrical conductor passed through a wall of said body and making an electrical connection 25 with said mercury.

30 4. A portable calomel half cell comprising a hollow glass body which is completely closed and sealed; a tubular glass container enclosed in said glass body but spaced therefrom throughout its length; said glass container being composed of fritted glass for the major portion of its length but having both ends composed of solid glass, the lower end being closed; the upper end of the glass container being open and being fused to the upper end of the hollow glass body; a transverse glass 35 partition integral with said body and closing the lower of the same; an electrical conductor passing through said partition and into the space between said body and said container; mercury completely filling all the space between said body and said container; calomel paste substantially filling the tubular glass container; and a porous plug closing the tubular glass container and protecting the calomel paste therein.

40 5. A portable calomel half cell comprising a hollow generally cylindrical glass body having an integral tubular re-entrant portion spaced therefrom and providing a calomel paste container entirely within the cylindrical glass body; a transverse wall closing said glass body near the lower end, said transverse wall being spaced from the lower end of the glass body and providing therewith a cup-like recess at said lower end; an electrical conductor; cement filling the cup-like recess and securing the electrical conductor to the hollow glass body; another conductor electrically connected to the first-named conductor and passing through said transverse wall into the space 45 between the glass body and said tubular re-entrant portion; mercury filling all the space between the hollow glass body and the tubular re-entrant portion; the tubular re-entrant portion having fritted glass walls extending nearly its entire length but being of glass of the same 50 composition as the hollow glass body at the end thereof which is remote from said transverse wall, said end being fused to be integral with the hollow glass body.
